CLAIM

The ornamental design for a hooded enclosure for capture devices as shown and described.

DESCRIPTION

FIG. 1 is a perspective view of the hooded enclosure for capture devices;

FIG. 2 is a front elevation of FIG. 1;

FIG. 3 is a back elevation of FIG. 1;

FIG. 4 is a right side elevation of FIG. 1;

FIG. 5 is a left side elevation of FIG. 1;

FIG. 6 is a top plan view of FIG. 1; and,

FIG. 7 is a bottom plan view of FIG. 1.

The broken lines shown in the drawings illustrate portions of the hooded enclosure for capture devices that form no part of the claimed design.

1 Claim, 7 Drawing Sheets
